UNITED STATES PATENT OFFICE.

GEORGE BESTER McKINNEY, OF BARRY, ILLINOIS.

MERRY-GO-ROUND.

No. 819,580.

Specification of Letters Patent.

Patented May 1, 1906.

Application filed August 4, 1905. Serial No. 272,664.

To all whom it may concern:

Be it known that I, GEORGE BESTER Mc-
KINNEY, a citizen of the United States, and a
resident of Barry, in the county of Pike and
5 State of Illinois, have invented a new and Im-
proved Merry-Go-Round, of which the fol-
lowing is a full, clear, and exact description.

This invention relates to a class of rotatable
machines employed for the rapid whirling
10 movement of one or more persons through
the air as a source of amusement, and has for
its object to provide novel details of construction
for a machine of the character indicated
which are extremely simple and durable,
15 adapt the same for the simultaneous rotation
of one or more individuals, and enable those
mounted upon the machine to communicate
rotary motion thereto by hand and foot
power in a convenient manner, thus afford-
20 ing amusement and healthful exercise to the
riders on the machine.

The invention consists in the novel con-
struction and combination of parts, as is here-
inafter described, and defined in the subjoined
25 claims.

Reference is to be had to the accompany-
ing drawings, forming a part of this specifi-
cation, in which similar characters of refer-
ence indicate corresponding parts in both
30 views.

Figure 1 is a plan view of the merry-go-
round machine; and Fig. 2 is an enlarged
partly-sectional side view of the details of
35 one seat and propelling means connected
therewith, the line of section and view point
being respectively indicated by the broken
line 2 2 and arrows shown in Fig. 1.

The generic features of the invention em-
body a suitable circular track, means for ro-
40 tatably supporting a plurality of seats on the
track free to traverse the same, and means
for transmitting orbital rotary motion to the
seats produced by exertion of manual energy
and foot-power by occupants of the seats.

45 In the drawings that illustrate the pre-
ferred means for carrying into effect the in-
vention, 5 represents a circular track of any
preferred diameter supported horizontally by
a suitable foundation. (Not shown.) A
50 post 6 is erected at the center of the track 5,
and upon the upper end of the post a whirling
frame is supported for rotation above the
track 5, said frame comprising a central hub
7, which is loosely mounted upon the post 6,
55 and a plurality of arms 8, that radiate at
equal distances apart from the hub. In the

present construction for the merry-go-round
six arms 8 are provided, which are disposed
oppositely in pairs and have an equal length
that projects them a proper distance outside
6c of the track 5.

The arms 8 are spaced apart and suitably
stayed laterally by two braces 9 10, secured
upon the arms by bolts *a* or other means, the
brace 9 being positioned nearly above the
65 track 5 and the brace 10 near the outer ends
of the arms, both braces being disposed con-
centric with each other and with the center
of the post 6, as appears in Fig. 1. Upon the
outer extremity of each arm 8 a seat 11 is
70 mounted and secured, and said seats may be
given any preferred form, all the seats facing
in the same direction, as indicated by the
curved arrow *x*, which shows the direction
for rotating the whirling frame and seats
75 thereon.

A bracket-frame 12 is secured pendent on
each arm 8 near the inner brace 9, and on
the lower end of each bracket-frame a
traction-wheel 13 is journaled, said similar
80 wheels all resting upon the circular track 5
and mainly supporting the whirling frame
and weight imposed thereon.

A rock-shaft 14 is supported free to turn in
boxes or the like on the braces 9 10 in front
85 of each seat 11 and parallel with a respective
arm 8, each shaft having a crank-arm *b* on
its inner end, that is connected with a respec-
tive wheel 13 by a pitman 15, which is piv-
oted by its ends on the end of the correspond-
90 ing crank-arm and at a suitable point on the
adjacent wheel 13, as appears for one wheel
in Fig. 2. On the outer end of each rock-
shaft 14 is securely mounted a rocking frame
16, each of these similar frames comprising a
95 handle-bar *c* and a foot-bar *c'*, spaced from
the handle-bar by a transverse frame-bar *c''*,
the latter being affixed at its center on the
end of a corresponding rock-shaft.

The merry-go-round apparatus that has
100 been described may be operated by any
number of individuals occupying respective
seats 11, each person resting his feet on a
foot-bar *c'*, that is in convenient position and
taking hold of the handle-bar *c*, that is di-
105 rectly in front of him.

It will be seen that the rocking movement
of the frames 15 will rock the shafts 14,
which will by a similar movement of a re-
spective crank-arm *b* transmit rotary motion
110 to the wheel 13, that is connected by a pitman
15 to the crank-arm.

As the riders are all supposed to work together in the manner described, the speedy simultaneous rotation of the traction-wheels 13 by manual effort and applied foot-power 5 will effect a rapid rotation of the whirling frame and seats thereon, so that by moderate efforts that are beneficial as exercise the riders may mutually enjoy the exhilarating amusement afforded by the rotation of the 10 novel machine.

Having thus described my invention, I claim as new and desire to secure by Letters Patent—

1. A merry-go-round, embodying a supported level circular track, an upright post central within the track, a whirling frame having a central hub pivoted upon the post, and further comprising a plurality of spaced arms radiating from said hub, and a brace 15 secured on the outer portions of the arms, a pendent bracket-frame on each arm, a traction-wheel pivoted upon each bracket-frame, said wheels resting upon the track, a seat on the outer end of each arm, rock-shafts 20 loosely mounted on the whirling frame, one ahead of each seat, means for transmitting rotary motion from each shaft when it is rocked, and means for rocking the shafts by 25 the occupants of the seats.

2. A merrygo-round, comprising a supported level circular track, an upright post central within the track, a whirling frame embodying a hub pivoted upon the post, a plurality of spaced arms radiating from the hub, and two brace-rings of different diameters secured on the arms, a seat mounted upon each arm at its outer end, a bracket-frame depending from each arm near the track, a traction-wheel pivoted on each bracket-frame and seated upon the track, 30 rock-shafts loosely mounted upon the whirling frame, one ahead of each seat, a crank-arm on the inner end of each rock-shaft, a pitman pivoted at its ends respectively on a crank-arm and an adjacent traction-wheel, 35 and a rocking frame secured on the outer end of each rock-shaft, said frames each comprising a foot-bar and a handle-bar spaced apart parallel with each other for movement with the feet and hands of the occupant of 40 an adjacent seat.

In testimony whereof I have signed my name to this specification in the presence of two subscribing witnesses.

GEORGE BESTER MCKINNEY.
